(57) **CLAIM**

The ornamental design for a gaming machine, as shown and described.

DESCRIPTION

FIG. 1 is a front top right perspective view of a gaming machine showing our new design;

FIG. 2 is a front bottom left perspective view thereof;

FIG. 3 is a front view thereof;

FIG. 4 is a right side view thereof;

FIG. 5 is a left side view thereof; and,

FIG. 6 is a top view thereof.

The center region is a display and has a surface which is transparent, translucent, highly polished or reflective. The planar back panel is a display and has a surface which is transparent, translucent, highly polished or reflective. The broken line showing of the remainder of the gaming machine forms no part of the claimed design.
